UNITED STATES PATENT OFFICE.

ROBERT E. GLASS, OF COLUMBUS, OHIO.

BURIAL CRYPT.

1,427,458.

Specification of Letters Patent. Patented Aug. 29, 1922.

Application filed October 27, 1920. Serial No. 420,058.

To all whom it may concern:

Be it known that I, ROBERT E. GLASS, a citizen of the United States, residing at Columbus, in the county of Franklin, State of Ohio, have invented certain new and useful Improvements in Burial Crypts; and I do hereby declare the following to be a full, clear, and exact description of the invention, such as will enable others skilled in the art to which it appertains to make and use the same.

This invention has to do with burial crypts in general and more particularly to the means for treating the gases that arise from the bodies placed therein, the object of the invention being primarily to provide means for supplying a neutralizing agent to the interior of the crypt from time to time so that the proper quantity will be continually exposed within the crypt, while egress of gases through the supply passage or duct, will be at all times prevented.

It is a further object of the invention to provide a particular equipment including a container that may be readily attached to the inner face of the crypt seal that is about to be set up, with a supply pipe that constitutes a filling duct for the container and which may be embedded in the plastic material of the seal, even when the latter is of very slight thickness.

Other objects and advantages of the invention will be understood from the following description.

In the drawings:

Figure 1 is a section taken vertically through a portion of a mausoleum, to include a series of superimposed crypts, of which the upper ones are open for the reception of caskets, while the lower ones are illustrated as sealed, and with the present invention installed.

Figure 2 is a section taken vertically through a seal equipped with the present invention, the section extending from front to back of the seal.

Figure 3 is a vertical section through a portion of a seal having the tube embedded in it, the section being at right angles to that of Figure 2.

Figure 4 is a detail perspective view of the supply tube.

Referring now to the drawings, there is shown a portion of a mausoleum that includes an outer wall 5 that is laid up with whatever material is desired to give the de-

sired appearance to the exterior and against this outer wall 5 is placed a lining 6 of hollow tiles, against which in turn, is poured or otherwise placed an inner wall 7 of concrete.

From the wall 7, there extend inwardly to the corridor 8 of the mausoleum, a plurality of crypts 9, separated by the horizontal partitions 10 and vertical partitions 11, it being noted that there is an uppermost member 12 forming the top of the uppermost crypt and corresponding to the partitions 10 and that there is a lowermost member 13 that corresponds also to the partitions 10 and that forms a bottom for the lowermost crypt.

In connection with each crypt there is employed a seal 14, that is a concrete slab that is fitted into the open end of the crypt and against the shoulder 15 that is formed by correspondingly enlarging the outer end portion of the enclosure of the crypt both vertically upwardly and laterally as illustrated. On each wall of each crypt is an enamel lining 16, the outer end edge of which touches the plane of the shoulder 15 and against the edge of the bottom lining the corresponding lower edge portion of the seal is placed. The seal is beveled so that its outer face is of less area than its inner face and there is provided a corresponding and continuous pocket between the edge of the seal and the corresponding walls of the crypt, to receive a filling 17 of grouting or other suitable material.

Each crypt drains to its rear end where there is a gutter 18 from which leads a duct 19 to a glass or earthenware receptacle 20 that holds quicklime or other material of absorptive and disinfecting nature.

The present invention has to do with the equipment built into and carried by the seal of each crypt, for neutralizing the gases therein, it being particularly noted that there is no provision for carrying gases to the outside atmosphere but that on the contrary, the gases within each crypt are treated within that individual crypt, while passage of gases from the crypt is positively precluded, even during the process of supplying liquid to the container that is carried against the inner face of the seal and from which container it rises in proper quantity, due to volatilization.

It will be noted that the seal 14 has embedded in it a U-shaped pipe including the vertical legs 20 and 21 and the connecting

BEST AVAILABLE COPY**2****1,427,458**

lower bight portion 22, lying in a common plane. The leg 20 is somewhat longer than the leg 21 and the upper end portions of the two legs are turned at right angles to the common plane of the legs and bight portion and in opposite directions. This pipe is embedded in the concrete of which the seal 14 is preferably formed so that the turned upper end portions 20' and 21' of the legs 20 and 21 respectively, extend through the outer and inner faces respectively of the seal. The portion 20' terminates flush with the outer face of the seal and is internally threaded to receive a plug 23, while the portion 21' extends beyond the inner face of the seal and has its extremity turned downwardly a short distance, as shown at 24, to enter the neck of a glass bottle 25 therebelow.

20 The bottle 25 is held against the inner face of the seal 14 by means of the upper and lower copper wires 26 and 27 that have their intermediate portions embedded in the concrete of the seal while their end portions, after being passed around the bottle, are twisted together to hold the latter in place.

It will be noted that the portion 24 of the pipe does not fit the neck of the bottle, so that such volatile liquid as the bottle may contain, may pass gradually from it to combine with the atmosphere of the crypt.

When the crypt is empty, the seal lies within it, as illustrated in the upper portion of Figure 1, while the bottle 25 stands conveniently near and ready to be wired in place after the seal has been removed for that purpose.

When initially installed, the bottle 25 is filled with formaldehyde or equivalent material and an additional quantity may be supplied to the U-shaped tube to rise in both legs and constitute a gas seal for the pipe, the plug 23 being then inserted. When it becomes necessary to renew the supply in the bottle 25, the plug 23 is removed and the proper material is injected into the U-shaped pipe, from which it flows to the bottle, there remaining after each such operation a quantity of fluid in the pipe reaching to the level of the lower side of the portion 21'. By renewing the fluid prior to the complete volatilization of that which is within the pipe, egress of gas will be of course prevented when the stopper 23 is removed.

It will be particularly noted that by turn-

ing the end portions 20' and 21' at right angles to the plane of the U-shaped portion of the pipe, such U-shaped portion may be completely embedded in a seal or concrete slab having a thickness very little greater than the exterior diameter of the pipe, with a consequent saving in weight and material of the slab.

While the tube and container for the disinfectant are provided in direct connection with the seal, it will, of course, be understood that when desired, it may be provided in connection with a side or back wall, the seal constituting the front wall of the crypt when it is closed.

What is claimed is:

1. The combination with an hermetically sealed crypt, of an open-mouthed disinfectant container therein, and a U-shaped filling duct leading into the crypt from its exterior and having the ends of its legs disposed in the same plane and extending in opposite directions, one of the said ends being arranged to receive disinfectant and the other end being arranged in filling relation to the container.

2. The combination with an hermetically sealed crypt of means for renewing disinfectant thereto comprising a U-shaped tube embedded in a wall thereof with the legs and connecting bight portion in a common plane parallel with the inner face of the wall, the ends of the tube extending in opposite directions and at right angles to the common plane of the legs and bight portion through the inner and outer surfaces of the wall respectively and above the bight portion, and an open-mouthed receptacle held to the inner face of the wall in position to receive disinfectant from the inner end of the tube.

3. A seal for a crypt having an hermetically sealed U-shaped tube embedded therein with its legs and bight portion in a common plane parallel with the inner face of the seal, the end portions of the tube above the bight portion extending through the inner and outer faces of the seal respectively, with the end portion through the outer face at a higher elevation than the end portion through the inner face, a receptacle disposed to receive from the inner end portion of the tube and a removable closure for the outer end of the tube.

In testimony whereof, I affix my signature.

ROBERT E. GLASS.
